CABLE CONNECTOR

Johannes Wilhelm Hofmann, Radebeul-Kotzschkenbroda, near Dresden, Germany, assignor to Burndy Engineering Co., Inc., New York, N. Y., a corporation of New York

Application October 7, 1936, Serial No. 104,446
In Germany October 16, 1935

1 Claim. (Cl. 24—243)

This invention relates to cable connectors and more particularly relates to connectors for automatically maintaining the clamping pressure between the jaws of the connector and cable where 5 cross-sectional yielding of the conductor occurs.

Aluminum cables have come into extensive use, and prior connectors for cables were unsatisfactory due to the relatively high ductility of the aluminum. The clamping pressures of the connector jaws resulted in a cross-sectional yielding and compression of the aluminum cable, reducing the cross-sectional area. Although the prior connectors were satisfactory for copper cables, they failed with the light weight conductors 10 because of the relative ease of compressibility of such conductors.

The contact resistance between an aluminum cable and the connector increases when the cable is compressed due to the reduction in the contact 20 pressure. The increased contact resistance results in heating at the connector joint, which adds to the ductility of the metal to further increase the yielding by the cable. Alternate warming and cooling of the conductor due to varying 25 load current conditions aggravates this phenomenon until the connection is finally destroyed by fusing.

Faults are expensive to repair, particularly in crowded and heavily loaded networks. Prior 30 clamps, designed with transverse jaws tightened together by bolt and nut, required periodic tightening to maintain the contact pressure at the connection to prevent fusing. Spring washers were inserted between the bolts and jaws in an attempt to maintain the clamping pressure 35 constant. However, the washers were unsatisfactory since they limited the requisite high clamping pressures.

In accordance with this invention, one or more 40 of the jaws of the cable connector are designed as elastic or compliant members. The compliant jaw automatically adjusts itself to any varying cross-sectional conditions of the conductors to maintain the contact pressure with the cable substantially constant. Fusing and faults are 45 obviated since the contact resistance and contact pressure at the cable connection is unaffected by changes in the cross-sectional area of the cable as in prior devices. The cable connector of this invention automatically compensates for varying 50 conditions and requires no attention after it is installed and is accordingly particularly suitable for inaccessible and underground cable constructions. The connector may be used to join two 55 dissimilar conductors, for example copper and

aluminum, without deleterious corrosive effects.

It is accordingly an object of this invention to provide a novel connector particularly useful for light weight conductors such as aluminum.

It is another object of this invention to provide a novel cable connector having compliant jaw members.

It is a further object of this invention to provide a novel cable connector which joins cables of varying shapes and cross-sections and automatically maintains the contact resistance and pressure at the connection substantially constant.

It is still a further object of this invention to provide a novel cable connector for joining two cables of different metals such as copper and 15 aluminum.

These and other objects of the invention will become evident in the following description of several modifications taken in connection with the drawing, in which:

Figure 1 is a modification of one embodiment of the cable connector showing one compliant jaw member.

Figure 2 is a side view further illustrating the modification of Figure 1.

Figure 3 is an end view of another modification for a cable connector in accordance with this invention; and

Figure 4 is a side view of the modification of Figure 3.

Figure 5 is an end view of a modified form of the cable connector having two compliant members; and

Figure 6 is a side view of the modification of Figure 5.

Referring to Figures 1 and 2, a modification of the invention is illustrated for mechanically and electrically connecting a branch feeder 10 to a main cable 11 having a larger cross-sectional area than cable 10. These cables are illustrated as 40 stranded conductors, cable 10 having a circular section and cable 11 a triangular section. It is to be understood that the connectors of the present invention may be readily designed by those skilled in the art to be applicable for conductors 45 of equal or different dimensions and cross-sectional configurations.

Clamp jaws 12 and 13 are secured in position over the cables 10 and 11 by screw members 14 50 which pass through screw holes or circular openings 15 in jaw member 12 and are anchored in jaw member 13 at the threaded portions 16 thereof. A central pressure plate 17 is provided to mechanically separate the two conductor 55

cables 10 and 11 and to equalize the pressures upon each cable.

The jaw members 12 and 13 and the pressure plate 17 are provided with longitudinal grooves or 5 arched seat corresponding to the configuration and size of the co-acting conductor portions in contact therewith. It has been found that for stranded cables, the longitudinal grooves co-acting with the cables need not be serrated to maintain the mechanical connection for cables under 10 tension. However, serrations may be added as is well known in the art.

The pressure plate 17 is not attached to the jaw or screw members, but is floatingly suspended between the cables 10 and 11 and the screws 14. Projections 18 extend from pressure plate 17 at the screws 14 to guide the plate vertically and prevent dislodgement thereof. Plate 17 adjusts itself in proper position between the 15 jaws and conductors and transmits and equalizes the pressure between the cables between the opposed jaws 12 and 13.

This invention particularly resides in the provision of the compliant jaw member 12 for the 20 cable connector. The outer portions or wings 19 of the jaw 12 are provided with holes 15 having a diameter larger than the screw 14, but smaller than the head 20 of screw 14. The compliant jaw 12 is made of a metal having a high elasticity and 25 may be a suitable steel, bronze or heat-treated aluminum alloy.

The unassembled shape of compliant member 12 is shown somewhat exaggerated by the dotted position. In assembling the connector, the screw 30 heads 20 tighten down upon wings 19 until a suitable pressure exists between the jaws and the cables. Jaw 12 is designed with sufficient cross-sectional area and elasticity so that it is still under elastic deformation under the maximum 35 screw pressure exerted in the field. Accordingly, member 12 is designed with a normal W shape shown by the dotted position so that after assembly the wings 19 will assume a somewhat level position as illustrated. A relative movement occurs between the wings 19 and the screw heads 40 20. Accordingly, the screw holes 15 in wings 19 are made of sufficient diameter to permit this movement and the wings 19 are somewhat curved as shown to permit the relative sliding with minimum 45 frictional impedance.

The assembled cable connector as illustrated in Figure 1 provides the requisite mechanical pressure for maintaining the cables 10 and 11 in position and also serves as an electrical connection 50 between the cables. Member 12, elastically deformed when assembled, maintains the requisite pressure between cables 10 and 11 and the pressure plate 17 floatingly inserted therebetween. Any contraction in the cross-sectional area of the 55 cables 10 or 11 or both will be instantly compensated for by the compliant jaw 12, the central portion 21 of which will move against cable 10 as will now be evident to those skilled in the art. Jaw 12 acts as a compressed spring against 60 the cables and any slight contraction in the cables will be followed by the spring-like action of the central elastically stressed portion 21. An important advantage of the construction of this invention resides in that the compensation instantaneously and automatically occurs irrespective of 65 whether cable 10 or cable 11 or both yield. The pressure plate 17 being floatingly suspended between the screws 14, adjusts itself vertically and

maintains an equalized pressure between the cables 10 and 11. The lip projections 18 of the plate 17 around screws 14 prevent transverse displacement of the plate.

Referring now to Figures 3 and 4, a modified 5 form of the invention is illustrated. The conductors 22 and 23 are shown as circular but of different sizes. The jaw members 24 and 25 are assembled together with the bolts 26 in a manner similar to the hereinabove described modification. 10 Bolts 26 are shown in position with the nuts 27 co-acting against the flat rectangularly shaped rigid jaw 24. The floating pressure plate 28 corresponds exactly to the plate 17 of Figures 1 and 2, and has longitudinal grooves to conform with 15 the conductors 22 and 23. The jaw member 25 in this modification is the compliant member corresponding to the jaw 12 of Figures 1 and 2. The dotted shape of jaw 25 illustrates its original form before bolting into position. The wings 29 of 20 jaw 25 are preferably designed to be horizontally disposed after tightening and assembling as shown. The central portion 30 of jaw 25 is, in this modification, elastically stressed against the conductor 23 to provide the same action as already described. The heads 31 of bolts 26 are rounded at the portion 32 thereof, co-acting with the flat wings 29 to prevent frictional resistance 25 during assembly.

Another modification of this invention is illustrated in Figures 5 and 6, utilizing two elastic 30 jaw members 33 and 34 assembled in position with bolts 35. Jaw 33 is shown similar to jaw 12 of Figures 1 and 2; and jaw 34, to jaw 29 of Figures 3 and 4. The compliant jaws 33 and 34 35 co-jointly perform the functions of the individual jaws of the other modifications and provide greater elastic compensation than the other modifications.

The cable connector of this invention may be 40 used to join two dissimilar metallic conductors such as copper and aluminum. Corrosive effects between the cables may be eliminated by using a neutral metallic floating pressure plate between them. The plate could be constructed of two 45 metals such as copper and aluminum to contact the conductors for preventing corrosive action therebetween.

Although several modifications of the present 50 invention have been illustrated and described, other modifications are feasible which fall within the broader spirit and scope of this invention, and accordingly, this invention is not intended to be limited except as set forth in the following claim.

What is claimed is:

In an electrical connector for electrically and mechanically clamping one cable to another cable, having two opposed clamping plates with clamping means positioned on each side of the cables clamped in the connector, a clamping plate made 60 of sheet metal of uniform thickness and having a centrally formed cable engaging arched seat with outwardly extending wing portions integral therewith for engagement with the clamping means adjacent the ends thereof, thereby providing 65 between said arched seat and said wing portions, sections having sufficient resiliency to compensate for changes in dimensions of the cable supported in the electrical connector, and means associated with said wings providing for relative 70 movement between the clamping means and said wings during the flexing movement of the wings.

JOHANNES WILHELM HOFMANN.
